DESIGN FOR AN EMBROIDERED TRIMMING

Michael B. Kaplan, New York, N. Y.

Application November 9, 1939, Serial No. 88,135

Term of patent 3½ years

To all whom it may concern:

Be it known that I, Michael B. Kaplan, a citizen of the United States of America, residing in New York city, in the Borough of Manhattan, county and State of New York, have invented a new, original, and ornamental Design for an Embroidered Trimming of which the following is a specification, reference being had to the accompanying drawing, forming part thereof, wherein the figure is a plan view of a piece of embroidered trimming showing my new design.

I claim:

The ornamental design for an embroidered trimming substantially as shown.

MICHAEL B. KAPLAN.
